METHOD OF OPERATING A CENTRIFUGAL SEPARATOR

Filed Dec. 8, 1936

UNITED STATES PATENT OFFICE

2,179,436

METHOD OF OPERATING A CENTRIFUGAL
SEPARATOR

Walter E. Smith, Honolulu, Territory of Hawaii

Application December 8, 1936, Serial No. 114,815

3 Claims. (Cl. 127—56)

This invention relates to centrifugal machines for separating sugar from the mother liquor and it is an object of this invention to provide an improved method of operation for a machine of the 5 class described which secures a more nearly complete separation of the mother liquor from the sugar and it is also an object of this invention to provide a machine of the type described of improved construction which permits of the operation of the machine in a manner to secure the 10 desired separation of the mother liquor from the sugar.

In the drawing, which shows a separator arranged for carrying out this invention, Fig. 1 is 15 a view, partly in elevation and partly in vertical section of a machine constructed in accordance with this invention; and

Fig. 2 is a plan view of one of the closures for 20 the top of the curb shown detached therefrom.

In the process of separating sugar from the mother liquor or molasses in a centrifugal separator, the extent to which the separation may be accomplished is limited by the viscosity of the molasses which causes it to adhere to the 25 sugar crystals as a thin film even under extreme centrifugal force. One way in which the viscosity of the molasses has been reduced, to render possible the complete removal thereof, has been by the application of water or other suitable 30 liquid to dilute the molasses but in this method some of the sugar is dissolved in the liquid applied. A further method of reducing the viscosity 35 of the molasses has been to heat the sugar and molasses mixture hotter than the most desirable temperature of 108° F. before placing the mixture in the centrifugal machine. This method, however, may cause redissolving of some of the sugar, especially when much molasses is present, and at 40 the speeds heretofore used, the mixture cools during centrifuging and the molasses is considerably cooler and its viscosity higher at the end of the centrifuging when it is desired to have the molasses heated and its viscosity low.

In accordance with this invention the mother 45 liquor and sugar are at the usual temperature of about 108° F. when placed in the separator and the separator is arranged to be closed so as to prevent the passage of air currents through the sugar mass and separator and the loss of heat 50 resulting therefrom. At the beginning of the operation the greater portion of the molasses is thrown off readily and as the speed is built up the film of molasses on the sugar crystals becomes thinner. In order to insure substantially 55 complete separation of the molasses from the

sugar, the speed of the separator is built up until it is operating at 25 to 30% above the previously normal speeds for commercial separators of the same size, that is, the speed of a separator, 40 inches in diameter, is raised to 1700 to 1900 5 revolutions per minute. The object of the increase in speed is partly to increase the separation due to the increase in centrifugal force, but principally to improve separation by reducing the viscosity of the materials by reason of increase 10 in temperature caused by the heat generated by the air friction of the basket rotating at this higher speed. This increase in temperature is sufficient to materially reduce the viscosity and prevent any increase in the viscosity of the molasses so that the molasses is readily separated 15 from the sugar and a much more nearly complete separation of the molasses from the sugar is secured. As the increase in the temperature of the molasses occurs when the film of molasses on the sugar crystals is very thin there is very little, if any, dissolving of the sugar in the heated molasses. Upon the closing of the separator at the start of the operation the air in the separator becomes saturated with moisture from the vapor 20 rising from the mother liquor and as the temperature of the air in the separator rises during the operation its ability to absorb moisture increases and there would be some tendency for the air in the separator to absorb moisture from the molasses on the sugar and render it more viscous 25 but this tendency can be overcome by admitting an amount of moisture, as in the form of steam, during the operation sufficient to keep the moisture in the air at the saturation point but insufficient to appreciably affect the temperature in 30 the separator or to provide surplus steam which will condense and dissolve some of the sugar. 35

In the drawing there is shown a centrifugal separator arranged for the carrying out of this 40 invention. Such a separator comprises a curb 1 in which a basket 2 is supported for rotation by a shaft 4 driven by a motor 6 which is supported by suitable supporting means, not shown. The motor 6 is of suitable design and power to drive 45 the basket 2 at the desired increased speed. The basket 2 is shown arranged to discharge through the openings 8 controlled by valves 10 to a chute 12 leading to the usual conveyor, not shown. The chute 12 is sealed into the bottom of the curb 1 so as to prevent leakage of air into the curb. A 50 valve or damper 14 is mounted in the chute to prevent admission of air through the spot while the separator is in operation.

To close the opening in the top of the curb 55

through which the basket is filled and through which the shaft 4 extends, semi-circular doors 16 are hinged to the inner rim of the top of the curb. The doors 16 meet along a diameter and 5 are cut away at the centers of their meeting edges, as at 16^a, to fit about the shaft 4. The usual discharge spout 18 for the mother liquor or molasses is extended so that its mouth is below the level of the molasses maintained in the 10 trough 20. Steam to maintain the air in the separator at the saturation point may be supplied to the curb through a steam line 22 which merely discharges inside the curb since it is not desired to apply the steam to the sugar to secure a washing effect.

Closing the various openings in the manner shown prevents the passage of air currents through the separator and the sugar mass therein and the loss of heat resulting therefrom and 20 the increasing of the temperature within the separator without the addition of a washing liquid, but with the degree of saturation maintained, makes the molasses sufficiently fluid to secure maximum separation thereof from the sugar 25 without loss through the dissolving of the sugar in either the molasses or a washing fluid.

What is claimed is:

1. A step in a method of separating sugar from the mother liquor consisting of centrifuging the

mother liquor from the sugar in a sealed centrifugal separator to prevent flow of air currents therethrough at a speed of rotation necessary to cause a rise in the temperature of the sugar mass sufficient to increase the fluidity of the molasses 5 during said separation.

2. In a method of separating sugar from the mother liquor the step of centrifuging the mother liquor from the sugar is a separator sealed against the passage of air currents therethrough 10 while raising the temperature of the sugar mass by the operation of the separator at a speed necessary to cause a rise in the temperature of the sugar mass sufficient to increase the fluidity of the molasses during said separation and maintaining the air in the separator in a saturated condition by the addition of moisture.

3. In a method of separating sugar from the mother liquor the steps of centrifuging the mother liquor from the sugar in a sealed separator 20 while raising the temperature within the separator by the operation thereof at a speed necessary to cause a rise in the temperature of the sugar mass sufficient to increase the fluidity of the molasses during said separation and maintaining the relative humidity of the air in the separator substantially constant.

WALTER E. SMITH.

CERTIFICATE OF CORRECTION.

Patent No. 2,179,436.

November 7, 1939.

WALTER E. SMITH.

It is hereby certified that error appears in the printed specification of the above numbered patent requiring correction as follows: Page 2, second column, line 9, claim 2, for "is" read in; and that the said Letters Patent should be read with this correction therein that the same may conform to the record of the case in the Patent Office.

Signed and sealed this 19th day of December, A. D. 1939.

Henry Van Arsdale,
Acting Commissioner of Patents.
